DESIGN FOR A RADIATOR GRILLE COVER FOR AUTOMOBILES

Willard L. Morrison, Lake Forest, Ill.

Application October 2, 1936, Serial No. 65,140

Term of patent 7 years

To all whom it may concern:

Be it known that I, Willard L. Morrison, a citizen of the United States, residing at Lake Forest, in the county of Lake and State of Illinois, have invented a new, original, and ornamental Design for a Radiator Grille Cover for Automobiles, of which the following is a specification, reference being had to the accompanying drawing, forming part thereof.

Fig. 1 is a front perspective view of the radiator

grille cover, wherein the shutters are shown in open position, and showing my new design.

Fig. 2 is a front elevational view of the device;

Fig. 3 is a side elevational view of the device;

Fig. 4 is a sectional view taken on line 4—4 of Fig. 3.

I claim:

The ornamental design for a radiator grille cover for automobiles, substantially as shown.

WILLARD L. MORRISON.
